UNITED STATES PATENT OFFICE.

EMANUEL L. SCHNEIDER, OF ANN ARBOR, MICHIGAN.

WATER-HEATER.

SPECIFICATION forming part of Letters Patent No. 595,211, dated December 7, 1897.

Application filed February 8, 1897. Serial No. 622,558. (No model.)

To all whom it may concern:

Be it known that I, EMANUEL L. SCHNEIDER, a citizen of the United States, residing at Ann Arbor, in the county of Washtenaw and State 5 of Michigan, have invented certain new and useful Improvements in Water-Heaters; and I do declare the following to be a full, clear, and exact description of the invention, such as will enable others skilled in the art to which it app-
10 pertains to make and use the same, reference being had to the accompanying drawings, and to the figures of reference marked thereon, which form a part of this specification.

My invention relates to instantaneous wa-
15 ter-heaters, and has for its object the improvement of devices burning gas or oil for heating water to be used for lavatory or culinary pur-
poses in the shortest time.

My invention consists particularly in the
20 original construction and arrangement of the superimposed pans found in many heaters of this character and in the provision of sheet-
metal forms between adjacent pans, each form
filling the dual office upon the lower and up-
25 per sides, respectively, of a spreader for the
ascending heated products of combustion and a runway through which the water introduced
at the top in its descent reaches each pan. A
considerable increase of water-heating sur-
30 face is obtained by the introduction of the
sheet-metal forms.

Each constituent element of my invention
is described in detail and its office, together
with the mode of operation of the whole, fully
35 explained hereinafter.

Referring to the accompanying drawings,
wherein like numbers designate like parts
throughout the several views, Figure 1 repre-
40 senters a vertical mid-sectional view of my
invention. Fig. 2 represents a top plan view
with pans and sheet-metal forms removed,
showing burner, gas and water pipe connec-
45 tions, and stop-cocks. Fig. 3 represents a per-
spective view of one sheet-metal form. Fig.
4 represents a vertical section of two pans de-
tached, one above the other, showing their
construction and manner of supporting one
upon the other. Fig. 5 represents a plan view
of one pan, the broken lines indicating the
50 position of the form related to that pan.

Considering Fig. 1, there will be seen a cas-
ing, usually of tinned sheet-iron, consisting
of a lower portion 1, provided with a horizon-
tal series of apertures 2, a body portion 3, hav-

ing an ornamental upper edge, and a py- 55
ramidal top 4, opening into and supporting a
cylindrical chimney 5. Chimney 5 is fixed to
top 4, the top being supported and secured
within casing portion 3 near its ornamental
edge in any convenient manner. (See Fig. 1.) 60
Through casing portion 1 passes water-sup-
ply pipe 6. At its outer end pipe 6 joins a
cut-off cock 7, which may itself be connected
to water-service pipes or a reservoir. With-
in the casing pipe 6 turns upwardly and passes 65
centrally through an ordinary crown or spray
gas-burner 8, terminating in a vertical and
screw-threaded orifice 9 of a cross-pipe or
catch-basin 10. Orifice 9 fills the office of a
pipe-coupling joining pipe 6 with a perpen- 70
dicular pipe 11. Pipe 11 near its upper end
is pierced by a number of holes 12, while its
extreme end is closed by a cap 13, as my in-
vention is customarily made. Burner 8 pos-
sesses a mixing-chamber 14, (see Fig. 2,) and 75
a pipe 15 leads from it through casing portion
1 to a gas-cock 16, which may be connected
with the supply of gas. Burner 8 is operated
upon the Bunsen principle. The stem 17 of
gas-cock 16 is hollow and permits gas to flow 80
through it. A second gas-cock 18 is joined
to stem 17, and projecting from cock 18 is an
igniting-tube 19. Though closed as regards
burner 8, gas may flow through the stem of
cock 16 and be admitted to tube 19 by cock 85
18. A jet from tube 19, in flame, will be turned
toward burner 8 as cock 16 is opened to ad-
mit gas thereto. The body portion 3 of the
casing is not permanently secured to the
lower portion 1. When it is desired to light 90
burner 8, portion 3 of the casing is lifted and
the jet of flame from igniting-tube or pilot-
burner 19 turned toward the main burner.
The act of directing burner 19 turns stem 17
of cock 16 and admits gas to main burner 8. 95
Parts 16 to 19 being of known construction
and operation need not be further explained.

In Figs. 1 and 2 will be observed a galva-
nized-iron heat-shield 20, fitting the casing in-
teriorly. 100

Again considering Fig. 1, catch-basin 10
will be seen to join two pipes, affording out-
lets therefrom. One of these pipes 21, after
passing through shield 20 and casing portion
3, is closed by a removable cap 22. The re- 105
maining outlet-pipe 23, after passing through
shield and casing, is bent downwardly to form
a spout 24. The shield or lining 20 is sup-

ported by pipes 21 and 23, as shown, and a part of the shield is cut away or a suitable orifice provided through which the jet of flame from tube 19 may reach the burner.

5 As it would unnecessarily add to the drawings, this orifice through the shield is not shown. To enable portion 3 of the casing to be readily removed and replaced, recesses 3^a 3^a are cut from the lower edge upon opposite sides, 10 and pipes 21 23 enter the recesses when portion 3 is placed upon portion 1 of the casing.

The shape of bottom pan 25 of the series or "stack" of pans appears in Fig. 1, and in Fig. 5 the position of the flanged apertures 26 is shown. Ordinarily the pans of my invention are rectangular, and apertures 26 are formed one near each corner, and it will be noted that the flanges 27 rise above the bottom of the pan, thus preventing water from 20 falling through the apertures until a certain depth has accumulated, while affording ample passage for hot gases. Central aperture 28 (see Fig. 5) is usually less in diameter than the others through the same pan and is enclosed by a flange 29, turned oppositely—that is to say, projecting below the bottom of the pan. Water at any depth flows freely through aperture 28 and drips from flange 29. Attention is called to the fact that central 30 aperture 28 and flange of bottom pan 25 direct the falling water into catch-basin 10, to be finally discharged through spout 24.

With the exception of the extra side walls 30, possessing the lower edge grooves 31, (see Fig. 4,) each of the remaining pans 32 33 34 is a substantial copy of bottom pan 25. Each has corner apertures 26, encircled by upturned flanges 27, and central apertures 28, surrounded by depending drip-flanges 29, in 40 all respects identical with those described in connection with pan 25. Side walls 30 guard the casing from heat and prevent the escape of gases. They extend entirely around each pan, except pan 25.

45 In Fig. 3 is represented in full the quadrupedal sheet-metal form 35, having the four points or feet 36 37 38 39, designed to rest in the corners and upon the bottoms of the pans 25 32 33 34, as indicated by broken lines in

50 Fig. 5. There are four of these forms (numbered 35 40 41 42) and they are arranged one in each pan, as shown in Fig. 1. Each form has upturned edges 43 and transverse wrinkles or baffles 44, and it will be understood that upon 55 the upper surface of the form the water spreads out between edges 43 in flowing toward the feet, while the lower surface of the form retards and spreads the ascending products of combustion. Each form has also a central aperture 45, numbered only once in Fig. 3, which fits somewhat closely the perpendicular pipe 11.

Let the parts be assembled as indicated in Fig. 1, pipe 11 being screwed into orifice 9 of 65 catch-basin 10, casing portions 3 and 4 being removed, whereupon it will stand perpendicularly and rigidly. Now unscrew cap 13 and

slip the pans and forms alternately by means of their central orifices upon the pipe 11. It will be noted (see also Fig. 4) that grooves 31, 70 edging the extra side walls of each pan, engage the upper edges entirely about the pan immediately beneath. Usually the catch-basin supports the stack of pans, which is very light even though water be flowing through 75 the system. Any other convenient support may obviously be introduced within the purview of my invention. Then a thimble or hood 46, having a threaded orifice adapted to engage the end of pipe 11, is placed thereupon 80 to receive internally the jets of water issuing from holes 12 and cause them to fall upon upper form 42. Cap 13 and the casing may now be replaced.

Assuming the burner to be lighted and the 85 water turned on, it is believed to be clear from the foregoing that the upper surface of every pan and form will be continually covered with water and their lower surfaces subjected to hot gases.

90 What I claim, and desire to secure by Letters Patent of the United States, is—

1. In a water-heater, the combination of a pan having a discharge-opening through the central portion thereof, and flanged openings 95 27, an outlet-pipe leading from said discharge-opening, a metal form supported in said pan and having a central portion arranged to cover the discharge-opening of said pan, and distributing portions adapted to cover said 100 flanged openings, piping for supplying water to said form, and a burner adapted to heat the pan and form, substantially as described.

2. In a water-heater, the combination of a pan having a discharge-opening through the 105 central portion thereof, and flanged openings 27, an outlet-pipe leading from said discharge-opening, a metal form 42 supported in said pan having a central portion arranged to cover the discharge-opening of said pan, and distributing portions adapted to cover said 110 flanged openings, the distributing portions of said form provided with transverse corrugations, piping for supplying water to said form, and a burner adapted to heat the pan and 115 form, substantially as described.

3. A water-heater, comprising a series of pans, each pan having a discharge-opening, flanged openings 27 and a flanged rim, the 120 pans being connected by walls 30, each wall adapted to form a seat for a pan above and being provided with a flange at its lower portion adapted to rest upon the flanged rim of the pan below, an outlet-pipe leading from the discharge-opening of the lowest pan, piping for supplying water, and a burner adapted 125 to heat said pans, substantially as described.

In testimony whereof I affix my signature in presence of two witnesses.

EMANUEL L. SCHNEIDER.
